MEANS FOR MOISTENING PIECES OF PAPER
AND LIKE MATERIAL

Benjamin James Bennett, Leicester, England

Application September 23, 1941, Serial No. 412,042
In Great Britain October 8, 1940

9 Claims. (Cl. 101—132.5)

This invention relates to means for moistening pieces of paper and like material, and has reference, more particularly, to means for applying a moistening agent to sheets or strips of paper or like material preparatory to being printed upon, but is not necessarily limited in this respect as it may be used for applying adhesive to or for moistening sheets, strips or like pieces of material already coated with adhesive for use for other purposes.

The present invention is applicable for use principally in association with a reproducing, recording, duplicating, or manifolding machine or apparatus wherein reading, advertising or/and illustrative matter is printed upon previously moistened copy sheets of paper from a master sheet or form on a printing cylinder or drum. In this respect the invention is mainly intended for use in association with rotary mirror script duplicating machines of the kind wherein copy sheets are individually moistened and passed between a mirror script master sheet, carried on a rotary drum, and a co-operating pressure roller whereby they are caused to receive, by impression thereon, copies of the mirror script or image from the master sheet.

As will be understood, the expression "mirror script" herein used means the matter or image formed in reverse manner on the master sheet by writing, typewriting, drawing or other known process, which matter or image is adapted to make non-reversed copies on the copy sheets.

In duplicating machines of the kind concerned, the moistening of the sheets is effected by their contact with a moistening device prior to their passage between the rotary drum and pressure roller.

It has been found by experience that for moistening the copy sheets a moistening device such as a stationary pad, felt or other absorbent strip or some similar body is preferable to a device of roller form since it is adapted to more efficiently moisten the copy sheets as they have a rubbing or wiping contact with it.

Where a moistening device of pad, strip or other non-rotating form has been provided and, as is customary, the copy sheets have been drawn through the machine by the pressure co-operation of the rotary drum and pressure roller, it has been necessary to separate the moistening device and feed table or other support for the copy sheets in order to provide a space between them to permit introduction of the forward edge of the copy sheet to the drum and roller so that it could be

taken hold of by them to be drawn through. After such introduction of the copy sheet contact between it and the moistening device was established so that as the sheet was subsequently drawn through, by the action of the rotary drum and pressure roller, it was moistened by passage in contact with said device. The moistening device is, of course, situated in front of, i. e. on the entrance side of the converging portions of the 10 drum and roller between which the copy sheet is introduced, and since during insertion of the copy sheet in the way and for the purpose mentioned the moistening device was not operative the result has been that a portion of the copy sheet, 15 corresponding to the distance the moistening device was situated from the line on which the drum and roller would nip the front edge of the said sheet, has not been moistened. With duplicating machines having a moistening device 20 of the type referred to it has not therefore been possible, so far as I am aware, to moisten the whole or practically the whole of a copy sheet prior to its passage between the drum and roller, consequently there has been a heading or forward marginal portion of the sheet which could not take an impression from the master sheet 25 and in cases where the copy matter might otherwise have extended nearer to the edge of the copy sheet a blank space has for the reason stated 30 had to be left and consequently wasted.

One of the objects of the present invention is to provide moistening means especially applicable for use in connection with a duplicating or like machine and adapted to moisten practically the 35 whole of a piece of paper such as a copy sheet.

Another object of the invention is to provide moistening means adapted to give much longer life in use before requiring renewal of the contacting moisture transmitting or applying member.

A further object of the invention is to provide moistening means with an improved arrangement for supplying the moistening agent to the 40 transmitting surface of the moistening device or member.

Another object of the invention is to provide a means of quickly saturating the moistening device or member, in the event of dryness, without 45 the operator having either to wait or remove the moisture transmitting portion of the moistening device or member while the moistening agent is poured on to the said portion or the latter is immersed in the said agent.

50 The invention also includes among its objects

improved regulation of the supply of the moistening agent from a container to said transmitting portion, and also to provide moistening means of a generally simplified construction by eliminating feed pipes and controlling valves from the supply system thereby reducing costs of production and maintenance.

According to this invention a moistening device or member is provided which is adapted to operate initially with turning motion for moistening the leading or forward marginal space of a piece of material to be treated, and then with rubbing or wiping contact with the said piece for moistening the remainder thereof while the said piece is being drawn past the moistening device or member.

In this respect the invention is advantageously applicable to the moistening of copy sheets in that the leading or forward marginal space which, as aforesaid, has previously been left blank can, if desired, be used for the reception of copy matter by impression from the master sheet or form in a duplicating or like printing machine.

In order that the invention may be more clearly understood and readily carried into practical effect, specific examples thereof as applied to a duplicating machine of the rotary mirror script type will now be described with reference to the accompanying diagrammatic drawings, wherein,

Figure 1 is a longitudinal sectional view of a duplicating machine showing one example,

Figure 2 is an elevational view of the moistening mechanism, per se, as viewed in the direction of the arrow A in Figure 1 but showing the moistening band as it appears after being moved forwards,

Figures 3 and 4 are side views of said moistening mechanism as seen in the direction of the arrows B and C (Figure 2) respectively,

Figure 5 is a general perspective view of the container from which the moistening agent is supplied to the moistening band,

Figure 6 is a detail sectional view showing means employed to secure the moistening band on its carriers,

Figure 7 is another detail sectional view illustrating the precise manner in which the ends of the band are secured upon the container,

Figure 8 is a diagram representing a piece of material in the nip of the moistening band and a co-operating bed roller,

Figure 9 is a somewhat similar diagram showing the same parts after the moistening device has been turned to feed the piece of material forwards into the nip of the printing cylinder or drum and the pressure roller,

Figure 10 illustrates a modification,

Figure 11 shows, in a flattened condition, a form of endless moistening band adapted for ready adjustment on its carriers, and

Figures 12, 13 and 14 are detail sectional views showing alternative arrangements for ensuring that the forward edge of a sheet is gripped between the moistening band and the bed roller, as will be hereinafter described.

Like parts are designated by similar reference characters throughout the drawings.

Figures 6, 7, 12, 13 and 14 are drawn to a larger scale than the remaining figures.

Referring to Figure 1 it will be seen that the machine includes a main frame comprising suitably shaped side members 1 which are spaced apart and connected by transverse rods 2. The

printing cylinder or drum 3 is rotatably mounted between the side frame members 1 and adapted to be turned by means of a handle 4 through the medium of gearing 5, 6. Co-operating with the cylinder or drum 3 is a pressure roller 7 which, in accordance with conventional practice, is rotatably mounted in spring-controlled bearings such as 8 carried by pivoted levers 9—one at each side of the frame. These levers 10 are adapted to be acted upon by bossed cam-like elements 10 rigidly secured to a cross shaft 11 which latter is turnable in its bearings by means of a lever 12. By turning the lever 12 in one direction or the other the degree of pressure exerted by the roller 7 upon the printing cylinder or drum 3 can be varied, according to requirements.

In this example, the moistening device is in the form of an endless band D carried by a transverse hollow cylinder or tube 13 sealed at both ends so as to constitute a container for a moistening agent, e. g. a spirituous medium such as alcohol, and by an appropriately spaced transverse roller or spindle 14 both rotatably mounted together with a co-operating bed roller 15 in suitable bearings in an auxiliary frame E located in front of the machine at an appropriate distance from the printing cylinder or drum 3 and its co-operating pressure roller 7. The arrangement is such that the distance x between the nip of the printing cylinder or drum 3 and the pressure roller 7 and the nip of the endless band D and the bed roller 15 is substantially equal to the leading or forward marginal space of a copy sheet hereinbefore referred to.

The endless band D is of a composite character comprising a pad 16 of felt, flannel or sponge rubber faced with wash leather 17 and lengths 18 of elastic webbing which are secured upon the container 13. The facing of wash leather assures a more even spreading of the moisture. The end portions of the pad 16 project beyond the leather facing and are reinforced by metal or equivalent strips 19 which latter are secured in position by superposed broader strips 20 of textile material stitched to the said pad in the manner shown more clearly in Figure 7. The portions of elastic webbing are formed into loops and secured at their inner ends between the pad 16 and the textile strips 20. The elastic loops projecting from the opposite ends of the pad are carried by bars 21 and 22 respectively. These two carrier bars are formed with holes to enable them to fit one on top of the other on a longitudinal series of screwed studs or pegs 23 provided on the container 13 (see Figure 5). When placed in position the bars 21 and 22 are clamped down upon the container 13 by means of tapped elements 24 screwed onto the studs or pegs 23. Each of the elements 24 is formed with a knurled head 24a as shown more clearly in Figure 6. The portions of elastic webbing therefore complete the band D and, in addition to providing a ready means of securing the band to the container, serve to tension the absorbent pad 16 about the roller or spindle 14.

The auxiliary frame E comprises spaced side members 25 connected by transverse rods such as 26 and 27 and is mounted upon the rear end of a table (bed or tray) 28. That is to say, the table extends in front of the moistening device with its rear end located adjacent to the converging portions of the band D and the bed roller 15 suchwise that copy sheets, fed by hand

or automatically, are accurately presented to the nip of the band and the bed roller. The auxiliary frame E, the entire moistening device and the table 28 together constitute a unitary assemblage capable of being removed from the main frame of the machine as occasion may demand. To enable this assemblage to be readily removed from and placed in position in the machine the sides of the table are formed with depending flanges 28a adapted to be received in and to slide between pairs of guides 29, 30 at opposite sides of the main frame. When the assemblage is inserted in the guides and pushed into position abutments 31 secured to the sides of the table come into contact with the frontal edges of the side members 1, thereby accurately determining the precise position of the moistening device with respect to the printing cylinder or drum 3 and the pressure roller 7. As shown in Figure 1, the moistening device is enclosed by a cover or casting consisting of a back plate 32 and an associated hinged front lid 33 both of which are attached to the side frame members 25.

The roller or spindle 14 is preferably of metal, whereas the co-operating bed roller 15 may be made of rubber, fibre, metal or any other suitable material. The bed roller 15, moreover, is yieldably mounted in which connection its ends are provided with pintles 15a working in slots 25a in the auxiliary frame members 25. In this way the roller 15 is permitted slight movement within limits relatively to the moistening pad 16 to compensate for differences in thickness of material passing between them, and this movement is controlled by two tension springs 34 serving to maintain presive co-operation of the roller and the pad. One of the springs 34 is anchored to the outer end of each pintle 15a and is made adjustable by reason of connection to an adjustable pin 35 (see Figures 2, 3 and 4). As shown more clearly in Figure 2, the roller or spindle 14 and the bed roller 15 are geared together for which purpose they are furnished at one side of the device with intermeshing gear wheels 36 and 37.

The container 13 is formed with a longitudinal series of small vents 13a and in the normal position of the container, i. e. the position indicated in Figure 1, the vents are disposed upwards so as to prevent escape of the contents 38 of the container. The container is also provided with a filler and a filler cap 39 at one end. The container may be provided with trunnions such as 40 (Figure 5) or with a central spindle for mounting it in the auxiliary frame E. In the case of trunnions these may be formed integrally with or fixed in discs employed to close the ends of the aforementioned hollow cylinder or tube. If a central spindle is provided, glands or/and suitable packings may also be provided at the ends of the container to prevent leakage of the contents.

The container is also fitted with an air regulating valve 41 whereby air is admitted thereto so that the moistening agent is caused to drip from the vents 13a when the latter are disposed downwards by reason of rotation of the container. The valve 41 is adjustable, e. g. by means of a screwed spindle, to regulate the pressure of air and consequently the issuance of the moistening agent from the container. By closing this valve the flow of the moistening agent from the container may be cut off entirely in the event of the band D being sufficiently permeated, or when the duplicating machine is not

in use. By operating the valve sufficiently the band may be quickly saturated in the event of it becoming dry as the result of not being used for some time, or of evaporation of the moistening agent. The valve is preferably of the ball and spring type in which the ball is pressed by the spring upon a conical seat. Alternatively, a needle valve or an air regulating valve of any other suitable type may be employed.

For the purpose of turning the band D first in one direction and subsequently in the reverse direction the container 13, in this example, is controlled by a tension spring 42 which, when permitted, functions to turn the container in the direction indicated by the arrow F (Figures 1 and 8) to move the pad 16 forwards, and intermediate mechanism, including a pivoted lever 43 and a roll 44, is arranged between the container and the printing cylinder or drum 3 suchwise that when the latter is rotated the roll and the lever are brought into and out of contact with each other whereby, while said last mentioned parts remain in contact, the container is turned against the action of the spring 42 and temporarily restored to its normal inoperative position in a loaded condition, but when contact between the roll and the lever is broken the container is released and consequently partially rotates in the same direction (F') as the printing cylinder or drum under the influence of said spring. Specifically, the spring 42 is located beneath the table 28 where it is anchored at one end to a tension adjusting screw 45 and connected at its other end to a length of wire cable 46. This cable is passed around a pulley 47 which is mounted in a U-shaped bracket 48 secured beneath the table, whereupon it extends up through a slot 28b in said table and is secured to the container 13 at or near one end thereof. The trunnion 40 at the opposite end of the container has rigidly secured thereto a pulley 49 which is connected to a curved end of the lever 43 by means of a short length of wire cable 50 (Figure 4). This lever is pivoted centrally upon a reduced end portion 45a of the transverse rod 26 and at its free end is formed with a curved recess 43a for a purpose presently to be mentioned. A bar 51 carrying the roll 44 is attached to the appropriate end of the printing cylinder or drum 3 so that upon the said cylinder or drum being rotated in the usual way by means of the handle 4, the roll is brought into contact with the lever 43 the free end of which is thereby depressed. When the roll enters the recess 43a the attendant interrupts rotation of the printing cylinder or drum so that the lever is temporarily maintained in the position shown in Figures 1 and 8. By reason of the lever 43 being turned in the manner just described the container is positively driven against the influence of the spring 42 in an anti-clockwise direction—as viewed in Figure 1—and thereby restored to its normal inoperative position shown in that figure. If now rotation of the printing cylinder or drum 3 is continued, the roll 44 rides off the end of the lever 43 to effect release of the latter whereupon the container 13 is free partially to rotate under the spring influence. Consequently, the vents 13a in the container are inverted so that the moistening agent drips onto the inside and permeates to the outside of the pad 16, and a corresponding amount of turning motion is imparted to the band D and the co-operating bed roller 15 whereby a sheet s fed into the nip of the band and the bed roller (Figure 8) is fed forwards to the printing cylinder or

drum 3 and the pressure roller 7 (Figure 9), and at the same time a corresponding length of the sheet is moistened by rotary action of the pad portion of the band about the transverse roller or spindle 14. The degree of rotary motion permitted to the container 13 is limited by means presently to be described, but is just sufficient to enable the leading edge or end of the length of material fed forwards to enter the nip of the printing cylinder or drum 3 and the pressure roller 7, whereafter the container and hence also the band remains stationary while the remainder of the sheet s is drawn between the pad 16 and the bed roller 15, during which time the pad in effect operates with rubbing or wiping action on the sheet. In this way each sheet is completely moistened. The container 13 is positively driven in the reverse direction and restored to its inoperative position in the manner previously described.

As shown more clearly in Figure 3, the means for limiting rotary motion of the container in both directions consists of a lever 52 which is rigidly secured to one of the trunnions 42 and works between two spaced stops or abutments 53 and 54 attached to the appropriate side of the auxiliary frame E. By adjusting this lever or the two stops or abutments, different parts of the pad 16 can be brought round to the operative position to form the contactual portion when wear takes place.

Alternatively and for a similar purpose, the endless band and the container may, as already alluded to herein, be provided respectively with complementary means for adjustably securing the band on the container and the other carrier. According to one construction a band D¹ of the modified form depicted in Figure 11 is provided with two or more transverse series of eyelets 55 (or sockets) adjacent to each end and the container 13 is provided with a corresponding longitudinal series of studs or pegs or like projections (like the studs 23) with which one series of eyelets adjacent to each end of the band is engaged so that the ends of the band overlap on the container. When eyelets are provided in the band these may be a press fit on the studs, pegs or like projections. In another construction the eyelets are such as freely to engage the studs, pegs or like projections, and a clamping strip, similar to one of the bars 21, 22, formed with a corresponding series of holes is provided for engagement with the studs, pegs, or like projections over the overlapping ends of the band D¹ and is fixed by nuts so as to secure the band in position. Thus by unfastening the band and engaging different series of eyelets with the studs, pegs, or like projections, different contactual portions of the band can be brought into use as and when required. The eyeleted portions of the band may be reinforced by strips of fabric, felt, Celluloid, rubber, metal or other suitable material. In a further alternative, the band may be frictionally engaged with one or both of its carriers, so as to permit of its being both driven and adjusted.

Instead of a single spring 42 for controlling the container there may be a spring 42 at each side of the mechanism to check any tendency of the latter to twist. Moreover, a lever such as 43 for restoring the container to its inoperative position may be provided at either or both sides of the mechanism.

In another example of the invention the container 13 is controlled by a spring, such as a tension, torsion, spiral (clock) or like spring whereby

it is retained in its normal position, and intermediate gearing and lugs are arranged between the container and the printing cylinder or drum 3 suchwise that when the latter is rotated in the usual way the lugs are brought into and out of contact with each other whereby, while the lugs remain in contact, the container is partially rotated against the action of its spring and in the same direction as the printing cylinder or drum, and when the contact between the lugs is broken or ceases the container reverts to its original position under the influence of its spring. In the specific driving arrangement of this character shown in Figure 10, one lug 56 is mounted on one end of the printing cylinder or drum 3, the other, 57, is mounted on a gear wheel 58 arranged on the auxiliary frame between the cylinder or drum and the container 13, and a pinion 59 is mounted on the adjacent end of the container in mesh with the intermediate gear wheel 58. A return spring 60 is associated with the gear wheel 58 but, if desired, may be associated with the pinion 59 or directly with the container 13. In any event the spring is connected at one end to the selected gear wheel or the container, as the case may be, and at the other end to a suitable fixed part. Consequently when the container is driven by the lugs 56 and 57, a corresponding amount of turning motion is imparted to the band D and the co-operating bed roller 15 whereby a sheet fed into the nip of the band and the bed roller is fed forwards to the printing cylinder or drum 3 and the pressure roller 7, and at the same time a corresponding length of the sheet is moistened by rotary action of the band about the associated transverse carrier roller or spindle 14. The lugs are of such a length and so arranged relatively that during contact with each other the length of paper fed forwards is sufficient to enable the leading edge or end to enter the nip of the printing cylinder or drum and the pressure roller, after which contact between the lugs is broken or ceases whereupon the container reverts to and remains in its original position under the spring influence while the remainder of the sheet is drawn between the moistening device and bed roller, during which time the band in effect operates with rubbing or wiping action on the sheet.

Instead of adopting lugs as aforesaid a toothed segment or equivalent may be provided on the printing drum or cylinder 3 for engagement with a gear wheel arranged between the printing drum or cylinder and a gear wheel on the container. Alternatively, the driving arrangement between the cylinder or drum and the container may consist of mutilated gearing, or may include a one way clutch or free wheel device adapted to slip or to disengage at an appropriate time to produce the same result as the lugs.

In either of the examples described the container may be of circular, polygonal, e. g. hexagon, or other appropriate cross sectional shape and the associated roller or other carrier for the band may be of corresponding form. The said roller or other carrier may be constituted in the main or partly of absorbent material like the band.

As already alluded to herein, if desired, the band may be frictionally engaged with the container so as to be adjustable thereon and yet driven thereby. In such a construction either the inside of the band, or the surface of the container, or both, is or are roughened or furnished with a roughened covering so as to provide a gripping surface or surfaces. For instance, either or both of the surfaces may be provided by

grooves, transverse in the case of the band, or longitudinal in the case of the container, or by small prominences or the like. Alternatively, one surface may be formed with relatively small protuberances or projections and the other with corresponding hollows or cavities.

As will be appreciated, in the example last described the portion of the band which opposes the bed roller 15 operates with rotary action on the sheet to be moistened when the band is driven in the manner described, with rubbing or wiping action against the travel of the sheet when it reverts to its original position before the remainder of the sheet passes it, and with rubbing or wiping action when the band remains stationary after reverting to its original position. Likewise in the first described arrangement wherein the band is not restored to its original position until after the sheet has passed it, the said portion also operates with rubbing or wiping action, the complete device nevertheless being maintained in a fixed position in relation to the printing cylinder or drum. Consequently it is the portion of the band which opposes the bed roller or equivalent opposing member when the band remains stationary, when in use, that takes most of the wear and thus, when this portion becomes unduly worn, a fresh portion may be brought into use by appropriate adjustment as aforesaid.

In some instances it may be found desirable to make provision whereby when the moistening device is in its normal inoperative position, there is a small space between it and the co-operating bed roller 15 to receive the forward edge of a sheet *s* of material, this space being provided just in advance of the nip of the pad 16 and the roller 15 so as to make certain of the sheet being gripped by the pad immediately the latter next commences to turn, i. e. move forwardly. To this end the juncture between the forward end of the pad 16 and the elastic webbing 18 may be so arranged as normally to be located as indicated in Figure 12, thereby providing a space 61 for insertion of the forward edge of the sheet *s*. Alternatively, the forward end portion 16¹ of the pad 16 may be recessed or grooved to provide a space 62 for the intended purpose (see Figure 13). Or the bed roller 15 may itself be grooved as indicated at 15¹ in Figure 14 to provide the space required and also to form a stop up to which the forward edge of the sheet *s* can be fed when inserted into this space. In the latter arrangement, however, it would be desirable to drive either the roller 14 or the bed roller 15, e. g. by chain or gearing, from the container 13 to ensure return of the groove 15¹ to its correct normal position each time; or for the same purpose the bed roller 15 could be returned by spring or equivalent means to a suitably arranged stop.

The term "endless" used in the foregoing description and in the appended claims as applied to the band should be understood as meaning that such band may, in a literal sense, be of continuous form without ends or that it may consist of a pad or strip of material having its ends joined or connected. The latter form is the one preferred in which case the ends of the pad or strip may, to form the endless band, be directly fastened together in the manner hereinbefore described or connected by clips or other suitable fasteners preferably of a kind which permit of easy removal or unfastening to enable the band to be detached when necessary for adjustment as aforesaid or replacement by a new one; or

the ends of the pad or strip may be fastened or connected to loops or pieces of elastic webbing (as herein described) or to the opposite ends of an elastic or other insertion. The elastic webbing or insertion when provided keeps the band (of endless form) tensioned on its carrier means.

What I claim then is:

1. In a duplicating machine, in combination, 10 a printing drum, a co-operating pressure roller, means for rotating the printing drum, a moistening device including a rotatable member, spring means connected to said member and effecting rotation thereof for controlling said device and under the influence of which the device is caused to operate initially with turning motion, intermediate drive-transmitting means connecting the drum and moistening device and driving the latter in the reverse direction against the action of the spring means to restore it to its normal inoperative position at appropriate times, and a bed roller with which said device is arranged to co-operate, the construction and arrangement being such that when a piece of sheet material is fed into the nip of the moistening device and the co-operating bed roller, the said device operates initially with turning motion to moisten the leading marginal portion of the piece and to feed it to the nip of the printing drum and pressure roller whereupon the latter function to draw the remainder of the piece between the moistening device and the bed roller while said device operates with rubbing action, for the purpose herein specified.
  2. In a duplicating machine of the rotary mirror script type, in combination, a printing drum, a co-operating pressure roller, means for rotating said drum, a frame located in front of the machine at an appropriate distance from the printing drum and pressure roller, an endless moistening band which is carried by a transverse hollow cylinder sealed at both ends so as to constitute a container for a moistening agent and 40 by a spaced transverse spindle, said container and spindle both being rotatably mounted in the frame, spring means connected to the cylinder and urging it to rotate in one direction, an operative connection between the drum and cylinder effecting intermittent counter rotation of said cylinder, and a bed roller with which said band is arranged to co-operate, the construction and arrangement being such that when a piece of sheet material is fed into the nip of the band and 45 the bed roller the said band operates initially with turning motion to moisten the leading marginal portion of the piece and to feed it to the nip of the printing drum and the pressure roller whereupon the latter function to draw the remainder of the piece between the band and the bed roller while said band operates with rubbing action, for the purpose herein specified.
  3. In a duplicating machine of the rotary mirror script type, in combination, a printing drum, 55 a co-operating pressure roller, means for rotating said drum, a frame located in front of the machine at an appropriate distance from the printing drum and pressure roller, an endless moistening band which is carried by a transverse hollow cylinder sealed at both ends so as to constitute a container for a moistening agent and by a spaced transverse spindle, said container and spindle both being rotatably mounted in the frame, spring means connected to the cylinder and urging it to rotate in one direction, an 60
- 75

operative connection between the drum and cylinder effecting intermittent counter rotation of said cylinder, a bed roller with which said band is arranged to co-operate, and a table which is mounted in front of the moistening band and the bed roller with its rear end located adjacent to the converging portions of the last mentioned parts, the construction and arrangement being such that when a piece of sheet material is fed along the table and into the nip of the band and the bed roller the said band operates initially with turning motion to moisten the leading marginal portion of the piece and to feed it to the nip of the printing drum and the pressure roller whereupon the latter function to draw the remainder of the piece between the band and the bed roller while said band operates with rubbing action, for the purpose herein specified.

4. In a duplicating machine of the rotary mirror script type, in combination, a printing drum, a co-operating pressure roller, means for rotating said drum, a frame located in front of the machine at an appropriate distance from the printing drum and pressure roller, an endless moistening band which is carried by a transverse hollow cylinder sealed at both ends so as to constitute a container for a moistening agent and by a spaced transverse spindle, said container and spindle both being rotatably mounted in the frame to move to and from an inactive position of band-moistening activity, a bed roller with which said band is arranged to co-operate, tension spring means including a spring anchored at one end and provided at its other end with an operative connection to said cylinder acting to turn the container from its inactive position and hence also the band in the same direction as the printing drum, a pivoted lever mounted on the frame in connection with the container, and a roll on the printing drum, said lever and roll being so arranged between the container and the drum that when the latter is rotated the roll and lever are brought into and out of contact whereby, while these parts remain in contact, the container is turned against the action of the spring means and temporarily restored to its inactive position, but when contact between the roll and the lever is broken the container is released for turning movement in the same direction as the printing drum, the construction and arrangement being such that when a piece of sheet material is fed into the nip of the band and the bed roller the said band operates initially with turning motion to moisten the leading marginal portion of the piece and to feed it to the nip of the printing drum and the pressure roller whereupon the latter function to draw the remainder of the piece between the band and the bed roller while said band operates with rubbing action, for the purpose herein specified.

5. In a duplicating machine of the rotary mirror script type, in combination, a printing drum, a co-operating pressure roller, means for rotating said drum, a frame located in front of the machine at an appropriate distance from the printing drum and pressure roller, an endless moistening band which is carried by a transverse hollow cylinder sealed at both ends so as to constitute a container for a moistening agent and by a spaced transverse spindle, said container and spindle both being rotatably mounted in the frame to move to and from an inactive position to band-moistening activity, a bed roller with which said band is arranged to co-operate, spring

means whereby the container is normally retained in its liquid-supply active position, and intermediate gearing and lugs operatively connecting the container with the printing drum

5 suchwise that when the latter is rotated in the usual way the lugs are brought into and out of contact whereby, while the lugs remain in contact, the container is partially rotated to inactive position against the spring action in the same 10 direction as the printing drum, and when the contact between the lugs is broken the container reverts to its original position under the influence of the spring means, the construction and arrangement being such that when a piece of 15 sheet material is fed into the nip of the band and the bed roller the said band operates initially with turning motion to moisten the leading marginal portion of the piece and to feed it to the nip of the printing drum and the pressure 20 roller whereupon the latter function to draw the remainder of the piece between the band and the bed roller while said band operates with rubbing action, for the purpose herein specified.

6. In combination, a printing drum, an oscillatory paper moistening device mounted adjacent said drum and including a paper feeding member, a feed roll adjacent the path of said member and cooperating therewith upon the said device being at one end of its oscillatory movement, spring means operatively connected to said device and urging it to oscillate in one direction, and an operative connection intermittently oscillating the said device against the action of said 35 spring means.

7. In combination, a printing drum, a cooperating pressure roller, means for rotating the printing drum, an oscillatory paper moistening device mounted adjacent to said drum, means operatively connected to said device and causing

40 it to oscillate in one direction, an operative connection between the printing drum and the moistening device effecting intermittent counter rotation of said device against the action of the last 45 mentioned means, and a feed roller adjacent to the moistening device and actively cooperating therewith upon said device being at one end of its oscillatory movement, the arrangement being such that when a piece of sheet material is fed 50 into the nip of the moistening device and the cooperating feed roller, said device operates initially with turning motion to moisten the leading marginal portion of the piece and to feed it to the nip of the printing drum and pressure roller 55 whereupon the latter function to draw the remainder of the piece between the moistening device and the feed roller while said device operates with a rubbing action.

8. In a duplicating machine, wherein the sheet 60 is advanced from a feeding station to a printing unit and is subjected to sheet-moistening action en route, a rotative printing unit including a printing drum and a pressure roller cooperative to provide a sheet nipping point for the unit 65 and to advance the sheet through the printing stage by drum rotation; a sheet-moistening unit including an oscillatable liquid container, a moistening element movable with the container, and a pressure roll cooperative with the element to provide a sheet nipping point for the moistening unit, said container having portage for supplying liquid to the moistening element and having limits of oscillation such as to render the portage inactive for liquid supply in one extreme of the oscillation range and be active for such supply 70 75

in the opposite extreme of the range; said printing and moistening units having complementary means for moving the container by and during a predetermined range of drum movement to thereby move the container from its active to its inactive liquid supply position; and means operative to move the container in the opposite direction of oscillation during drum advance beyond such predetermined range; said units and means being correlated in operation to provide the following sequence cycle of activities during a revolution of the drum: with the sheet-moistening unit in its active liquid supply position, begin advance of the drum to move the moistening unit to its inactive liquid-supply position by 15 drum movement to prepare the sheet-nipping point for the reception of the sheet leading edge at such point to permit sheet positioning relative to such nipping point; during continuance of drum rotation move the moistening unit container to its active liquid-supply position and advance the sheet by the moistening unit to present the sheet leading edge to the sheet-nip-

ping point of the printing unit, and concurrently moisten the leading marginal portion of the sheet by advance of the moistening element therewith at the sheet-advancing speed; and thereafter 5 advancing the sheet by printing unit advance to complete the drum rotation and apply the printing impression, and concurrently maintain the position of the moistening unit in its active liquid-supply position to moisten the residue of the sheet length by rubbing or wiping action of the element during the sheet advance through the moistening unit.

10 15 20 9. A machine as in claim 8, characterized in that the drum rotation is manually provided and permits an intermediate dwell in machine operation, said dwell being timed to maintain the moistening container in its inactive liquid-supply position and maintain the moistening unit nipping point in its prepared condition to receive the leading edge of the sheet during the period of the dwell.

BENJAMIN JAMES BENNETT.
